COMBINATION LOCK

Charles S. Gehrie, Montclair, N.J., assignor to Presto
Lock Co., Division of Walter Kidde & Company, Inc.,
Clifton, N.Y.

Filed Dec. 15, 1971, Ser. No. 208,520

Term of patent 14 years

Int. Cl. D8—07

U.S. Cl. D8—129

FIG.1

FIG.2

FIG.3

FIG.4

FIG.5

FIG.6

FIG. 7

FIG. 8

FIG. 9

FIG. 10

FIG. 11

FIG. 12

FIG. 1 is a top plan view of a combination lock embodying my new design;

FIG. 2 is a side elevational view taken from the top of FIG. 1;

FIG. 3 is a side elevational view as seen from the bottom of FIG. 1;

FIG. 4 is an end view as seen from the left of FIG. 1;

FIG. 5 is an end view as seen from the right of FIG. 1;

FIG. 6 is a bottom plan view;

FIG. 7 is a top plan view of another embodiment of my design, this embodiment having the appearance furnished by the hasp entering an end of the combination lock;

FIG. 8 is a side elevational view taken from the top of FIG. 7;

FIG. 9 is a side elevational view as seen from the bottom of FIG. 7;

FIG. 10 is an end view as seen from the left of FIG. 7;

FIG. 11 is a view as seen from the right of FIG. 7; and

FIG. 12 is a bottom plan view.

I claim:

The ornamental design for a combination lock, as shown and described.
